UNITED STATES PATENT OFFICE.

EDWIN H. SMYTHE, OF EVANSTON, ILLINOIS, ASSIGNOR TO WESTERN ELECTRIC COMPANY, INCORPORATED, OF NEW YORK, N. Y., A CORPORATION OF NEW YORK.

SOUND REPRODUCER.

Application filed August 17, 1926. Serial No. 129,733.

This invention relates to sound reproducers employing direct-acting diaphragms.

The principal object of the invention is to increase the energy imparted to the air from 5 a sound radiating surface.

Another object of the invention is to increase the relative movement between stationary and movable walls of a direct-acting sound reproducer.

10 The invention provides a sound reproducer comprising a movable wall and a stationary supporting wall which are so related that the entire surface of the movable wall is free to vibrate in response to sound variations. According to a feature of the invention, substantially all the flexibility necessary to permit the movable wall to vibrate as a whole for 15 low frequencies is concentrated near the periphery of the structure and external to the movable wall.

In a specific embodiment of the invention a conical diaphragm, which is driven at the apex, and a frusto-conical supporting member are connected base to base by means 25 of an annular ring of extremely light flexible material, such as duralumin, having one or more peripheral corrugations. The connecting ring is rigid in the direction of the plane of the base of the diaphragm, but 30 is flexible in a direction perpendicular to the plane of the base of the diaphragm, and hence permits the diaphragm to move toward and away from the support in response to sound vibrations, but prevents the diaphragm from moving laterally with respect thereto, and also prevents the radial relief of air pressures from the space enclosed between the relatively moving member and the relatively stationary member.

40 According to a modification of the invention, the bases of the conical diaphragm and frusto-conical supporting member are cemented directly together, and the required flexibility is obtained by cutting a series of 45 slots close to the extreme outer edge of the supporting member.

The invention will be described in connection with the accompanying drawing, in which similar reference characters designate 50 similar parts in the different views, and in which:

Fig. 1 is a side view, partly in section, of a sound reproducer having a unilaterally flexible peripheral connection between the diaphragm and supporting member;

Fig. 2 is a fragmentary sectional view showing a modified form of peripheral connections;

Fig. 3 is a perspective view showing a sound reproducer in which flexibility is obtained by cutting a series of slots adjacent the periphery of the supporting member; and

Fig. 4 is a fragmentary view showing a modified method of slotting the supporting member.

The sound reproducer shown in Fig. 1 comprises a conical diaphragm 5 and a frusto-conical supporting member 6 which may be made of light stiff material, such as blotting paper. The truncated end of the supporting member 6 is fastened securely to a suitable standard 7. The member 8 is provided for connecting a driving member to the apex of the conical diaphragm.

The connection between the diaphragm 5 and the supporting member 6 is provided by means of an annular ring 9 of extremely light flexible material, such as very light gauge duralumin, having a single deep peripheral corrugation 10. The connecting ring 9 is slightly larger in diameter than the diaphragm and supporting member and is joined on opposite sides of the corrugation to the outer edges of the diaphragm and supporting member by means of cement 11. If desired, 85 the connecting member 9 may be provided with a plurality of peripheral corrugations 12 as illustrated in Fig. 2.

The connecting ring 9 may be formed in any suitable manner, such as by passing a flat strip of very light gauge duralumin between properly shaped rollers adapted to form a channel of deeply corrugated cross-section and circular in form. This construction provides a pleated connecting ring which is inherently flexible across the plane of the corrugation, but is inherently rigid in the direction of the plane of the corrugation so that it will readily move in and out but will not buckle as the entire surface of the diaphragm 100 vibrates.

In the modification of the invention illustrated in Fig. 3, the diaphragm and supporting member are cemented together base to base. The flexibility necessary to permit the entire surface of the diaphragm to vibrate is provided by cutting a series of slots 13 disposed as closely as possible to the extreme outer edge of the frusto-conical supporting member, and preferably cut obliquely to 110

further reduce the resistance offered by the connecting fingers of material to axial movement of the diaphragm. A strip of light flexible cloth 14 is pasted over the slots 13, in order to avoid any substantial air leakage through the slots. The flexible cloth strip 14 may be pasted only along its inner and outer edges so that it will not increase the transverse rigidity of the supporting member 5 in the zone that it covers. The shape and disposition of the slots adjacent the peripheral margin of the supporting member may be varied as desired to reduce the constraint of the supporting member upon the diaphragm for example, being made triangular 10 as illustrated in Fig. 4.

Sound vibrations imparted to the apex of the conical diaphragm will tend to cause the entire surface of the diaphragm to vibrate 20 as a unit and produce a greater relative movement between the surfaces of the diaphragm and supporting members. This produces a greater velocity of air movement into and out of the space between the diaphragm and 25 supporting member and improves the response in the lower part of the musical scale.

The invention is also capable of other modifications and adaptations without departing from the scope and spirit of the invention 30 as defined in the appended claims.

What is claimed is:

1. A sound reproducer comprising a direct-acting diaphragm and a supporting member forming a partial enclosure, and a unilaterally flexible folded member connecting said diaphragm and said supporting member. 35

2. A sound reproducer comprising a direct-acting conical diaphragm and a supporting member forming a partial enclosure, and 40 means including a V-shaped hinge joining the outer edges of said diaphragm and said supporting member to form a closure therebetween.

3. A sound reproducer comprising a conical diaphragm driven at the apex, a supporting member therefor forming a partial enclosure, and a pleated member secured to said diaphragm and said supporting member, said pleated member being rigid in the direction 50 of the plane of the base of said diaphragm but flexible in a direction perpendicular to the plane of the base of said diaphragm.

4. A sound reproducer comprising a conical diaphragm driven at the apex, a frusto-conical support for the base of said diaphragm, and means including an annular pleated member of slightly different outer diameter than the bases of the diaphragm and the support for connecting said support and 55 said diaphragm together.

5. A sound reproducer comprising a large direct-acting diaphragm, a stationary support for said diaphragm spaced therefrom, and means providing a flexible connection between said diaphragm and said support, said means being positioned within the confines of the outer edges of said diaphragm and said support and being rigid in the direction parallel to the base of the diaphragm. 65

6. A sound reproducer comprising a conical diaphragm driven at the apex, a frusto-conical support for the base of said diaphragm, the bases of said diaphragm and said support being substantially equal and spaced apart laterally and means for connecting the 70 bases of said diaphragm and support comprising a member which is rigid in the direction of the plane of the base of said diaphragm and is flexible in a direction perpendicular to the plane of said base. 80

7. A sound reproducer comprising a conical diaphragm driven at the apex, a frusto-conical support, the bases of said diaphragm and said support being spaced apart and a ring of extremely light resilient material 85 connecting the outer edges of said diaphragm and support.

8. A sound reproducer comprising a conical diaphragm driven at the apex, a frusto-conical support, and an annular ring of extremely light spring metal having a deep 90 peripheral corrugation connecting the base of said diaphragm to the base of said support.

9. In a sound reproducing device, the combination of two dished members of equal base 95 diameters, one of said members having an aperture therein, a link connecting the bases of said members together, said link being flexible in the direction of the axes of said members and rigid in the direction perpendicular to the axes of said members, means for rigidly supporting one of said dished members at its aperture, and means connected to a point on the surface of the other of said members for imparting vibrational 100 forces thereto. 105

10. In a sound reproducing device, the combination of two conoidal-shaped members of equal base diameters, one of said members having an aperture therein, a corrugated 110 member for joining the edges of the bases of said conoidal-shaped members together, means for rigidly supporting said apertured conoidal-shaped member at its aperture, and means connected to a point on the surface of 115 the other of said conoidal-shaped members for imparting vibrational forces thereto.

In witness whereof, I hereunto subscribe my name this 12 day of August A. D., 1926.

EDWIN H. SMYTHE.
